三一九-3-

三一九-4-

FIG. 1 is a right side elevational view of a tractor loader body embodying our new design.

FIG. 2 is a left side elevational view thereof.

FIG. 3 is a front elevational view thereof.

FIG. 4 is a rear elevational view thereof.

FIG. 5 is a top plan view thereof.

The broken lines shown in the drawings are for illustrative purposes only and constitute no part of the claimed design.

We claim:

The ornamental design for a tractor loader body, substantially as shown and described.
